US0D1049365S

(12) **United States Design Patent** (10) **Patent No.:** **US D1,049,365 S**
(45) **Date of Patent:** **** Oct. 29, 2024**

(54) **MOUTHPIECE**

(71) Applicant: **ChemoMouthpiece, LLC**, Closter, NJ (US)

(72) Inventor: **David Yoskowitz**, Woodcliff Lake, NJ (US)

(73) Assignee: **ChemoMouthPiece, LLC**, Closter, NJ (US)

(**) Term: **15 Years**

(21) Appl. No.: **29/781,770**

(22) Filed: **Apr. 30, 2021**

Related U.S. Application Data

(62) Division of application No. 29/661,489, filed on Aug. 28, 2018, now Pat. No. Des. 924,389.

(57) **CLAIM**

The ornamental design for a mouthpiece as shown and described.

DESCRIPTION

FIG. 1 is a top, front, and left side perspective view of a mouthpiece showing my new design;

FIG. 2 is a front elevational view thereof;

FIG. 3 is a rear elevational view thereof;

FIG. 4 is a left-side elevational view thereof;

FIG. 5 is a right-side elevational view thereof;

FIG. 6 is a top view thereof; and,

FIG. 7 is a bottom view thereof.

The broken lines shown in the drawings represent portions of the mouthpiece that form no part of the claimed design.
